UNITED STATES PATENT OFFICE.

SIMON HAMBURGER, OF NEW YORK, N. Y.

DESIGN FOR A PAPER BOX.

SPECIFICATION forming part of Design No. 30,428, dated March 28, 1899.

Application filed February 28, 1899. Serial No. 707,222. Term of patent 7 years.

To all whom it may concern:

Be it known that I, SIMON HAMBURGER, a citizen of the United States, residing at New York, in the borough of Manhattan and State 5 of New York, have invented and produced a new and original Design for Paper Boxes, of which the following is a specification, reference being had to the accompanying drawings, forming a part thereof.

10 Figure 1 is a perspective view of a paper box, showing my new design; and Fig. 2 is a transverse section of the same.

As shown in the drawings, the leading feature of my design for paper or pasteboard 15 boxes is the shape of the opposite ends of the same, being irregular hexagons, comprising a lower rectangular part and an upper part in the form of a truncated gable and surrounded by a marginal rib projecting beyond the side 20 walls of the box.

A A are the opposite ends of the box, the same being of the same shape—that is, irreg-

ular hexagons—having a rectangular lower part a and an upper part a' of the shape of a truncated gable. The lower side walls B B', 25 the upper side walls B' B'', and the bottom C and top C' are all of rectangular shape. Extending around each of the hexagonal ends A A is a marginal rib b, which projects beyond the side walls, top, and bottom, so as to 30 impart a more ornamental finish.

Having thus described my invention, what I claim as new, and desire to secure by Letters Patent, is—

The design for a paper box, as shown and 35 described.

In testimony that I claim the foregoing as my invention I have signed my name in presence of two subscribing witnesses.

S. HAMBURGER.
